COOLER FOR COMFORT

Andrew A. Kucher, Dayton, Ohio

Application September 9, 1936, Serial No. 99,975

10 Claims.

(Cl. 62—130)

The present invention relates to refrigerating apparatus and particularly to coolers for personal comfort.

I have discovered that when refrigerated and dehydrated air is passed over the upper part of a human, for example, over the forehead, the relief from excessive environment heat is beyond that expected. I have also discovered that for comfort, it is not necessary and in fact not desirable 10 to cool the air to too low a temperature, because if the differential in temperature of the air passing over the head and the air about the other parts of the body is too great, the person cooled is disturbed by this difference.

15 One of the objects of the present invention is to provide a cooler for human comfort in which a container for refrigerating medium, such as ice, is used to cool the air and in which the air is directed over the container for cooling the same and 20 thereby causing a natural circulation of cooled air.

Another object of the present invention is to provide a refrigerant container which is relatively large in two dimensions but relatively thin 25 so that relatively large heat exchange surfaces, compared with the volume of the container, are presented to the air passing through the cooler and over the container.

The moisture from the moisture laden air condenses on the cooled surfaces of the cooler and in carrying out the foregoing objects, it is a further object of the invention to provide for conveying this condensate away from the cooling surfaces and prevent the revaporization of the 35 same.

Other and further objects and advantages will be apparent from the following description, reference being had to the accompanying drawing wherein a preferred form of embodiment of the 40 present invention is clearly shown.

In the drawing:

Fig. 1 is a perspective view of a bed showing one application of my invention.

Fig. 2 is a front view in elevation of the cooler; 45 Fig. 3 is a longitudinal sectional view of the cooler, the section being taken on line 3—3 of Fig. 2.

My invention is applicable to many uses and 50 is particularly useful for cooling the occupant of a bed. Therefore, I have illustrated the invention in connection with a bed 20. The cooler 21 is placed at the head portion of the bed above the pillow 22. Air passing through the cooler, contacts with the cooled surfaces thereof and con-

denses and drops toward the pillow and over the head of the occupant.

The cooler 21 comprises an outer casing having a main section 23 formed of sheet metal. This main section is open at the top and bottom. The bottom of the main section 23 is capped by the cap 24 preferably soldered in position. The top of section 23 is capped by the cover 25 which is readily removable so that access may be had to the chamber 26 formed by the section 23. A 10 series of holes are provided in the back 27 of section 23 to receive bolts 28 which are used for securing a hook 29 in desired adjusted position. This hook 29 is covered with rubber hose 31 or the like and extends over the top of the bed for holding the cooler 21 in position. Laterally spaced and rearwardly adjustable rubber bumpers 32 are suitably secured toward the bottom of the section 23 for suitably spacing the cooler from the bed.

20 A refrigerant container 35 formed of sheet metal, including a main section 36 and a permanently secured bottom cap 37 is removably carried within the casing 23. Spaced hooks 39 are carried by the upper part of the container 35 25 which are received by an air inlet opening 40 in the back 27 of main outer section 23. This opening 40 and the hooks 39 are arranged so as to locate the container 35 and hold the upper part thereof spaced from the walls of the chamber 26. 30 A clip 41 is secured to the lower part of the container 35 for spacing the lower part from the back wall of chamber 26.

An inlet opening 43 and an outlet opening 44 for air is formed in the front wall 45 of section 35 23 adjacent the upper and lower ends, respectively, of the ice container 35. When a refrigerating medium such as ice is placed in container 35, air in the passages 46, between the ice container and the main section of casing 23, will be cooled 40 and fall through the outlet opening 44. Of course the passages 46 will be replenished with air through inlet openings 40 and 43. Consequently cooled air will flow from the outlet 44 continuously as long as refrigeration takes place in the 45 passages 46. A generally arcuate shaped baffle 47 is secured at its lower end to the front 45 below the outlet opening 44 and at its upper end to the back 27 of section 23. This baffle 47 directs the air, which passes over the back of container 35, 50 toward the outlet opening 44, whence the cooled air passes across the head of the occupant of the bed.

The moisture from the air, passing through 55 passages 46, will condense on the walls of sec-

tion 23 and container 35 and flow downwardly on these walls. Some of the condensate will fall on the baffle 47 and drain toward the outlet 44. In order to prevent this water from passing through 5 the outlet 44, the baffle 47 is provided with a rise 49 adjacent the outlet 44 to form a trough 50. Water from the trough drains to the sides of baffle 47 and drops into the cap 24 which forms a receiving receptacle.

10 For practical purposes it is desirable to provide the container 35 with relatively large heat exchange surfaces as compared with the volume of the container. In order to accomplish this, the casing 23 and ice container 35 are flattened i. e., 15 the fronts and backs are wide and long as compared to the sides which interconnect the fronts and backs. The drawing Figs. 1 and 2 is approximately two fifths size and I have found that an appreciable and adequate temperature differential will be maintained for a period of several 20 hours with one filling of the ice container when the environment room temperature is in the neighborhood of 90° F. The container 35 is sufficiently wide for receiving the ice cubes made in 25 the household electric refrigerator and one tray of cubes will be sufficient to last several hours.

The present invention is particularly useful for cooling an occupant of a bed and is desirable for hospital and home use. The ice container 35 is removed preferably for emptying the water therefrom and filling the same with ice. The cap 25 of casing 23 is removed for this purpose. It is necessary to remove the casing 23 from the bed only when too much drip water is contained 35 within cap 24.

Thus it is apparent from the foregoing that I have provided a cooler for comfort which is relatively simple in construction and therefore can be manufactured cheaply. Substantially all parts 40 are formed of sheet metal. Also, this cooler requires only a readily available bulk refrigerant medium, for example, ice, solid CO₂, etc. Also, chamber 35 can be cooled by artificial refrigeration, however, it has been found that ice performs 45 the function satisfactorily. If a refrigerant, such as solid CO₂, is employed having sublimating characteristics, a fitting 51 would be attached adjacent the lower end of container 35 for removing the gas therefrom. A flexible tube 52 would 50 be connected to the fitting 51 to conduct the gas away from the occupant of the bed.

While the form of embodiment of the present invention as herein disclosed constitutes a preferred form, it is to be understood that other 55 forms might be adopted, all coming within the scope of the claims which follow:

I claim:

1. In combination with a bed having a head portion, a readily portable air cooler for personal comfort, said cooler comprising a refrigerant container, means forming with the said container an air passage along the side thereof and including an air inlet adjacent the top of the cooler and an

air outlet adjacent the bottom of the cooler and means for supporting said cooler on said head portion with the air outlet in position to discharge the cooled air upon the head of an occupant of the bed. 5

2. The structure described in claim 1 in which the size of the air passage is so related to the capacity of the container as to promote a positive gentle downflow of air through the passage.

3. The structure described in claim 1 in which 10 said outlet is formed to discharge the air in a sheet.

4. The structure described in claim 1 and including means for detachably securing the container to a wall of the first mentioned means. 15

5. The structure described in claim 1 in which the first mentioned means forms a chamber and in which means is associated with the said first mentioned means and the container for holding the container spaced from the walls of the 20 chamber.

6. A readily portable air cooler for personal comfort adapted for placement above the person to be cooled and in which the air is cooled by convection, comprising a flat container for bulk 25 refrigerant, a casing forming a flat chamber containing said refrigerant container, the walls of said casing being spaced from the container to form a narrow air path therebetween, said casing having an opening adjacent the top for the ingress of air to the passage and having an opening at the bottom for the egress of air from the passage, and means for supporting said cooler with the air outlet in position to discharge the cooled air upon the head of the person being 30 35 cooled.

7. In combination with a bed having a head portion, a readily portable self-contained air cooler for comfort, including a container for bulk refrigerant and a passage for air terminating in an outlet in the lower portion of the cooler, and means for detachably straddling the head portion of the bed and securing the cooler thereto in such position as to locate the outlet adjacent to the normal position of the head of the 45 occupant of the bed. 40

8. The structure defined in claim 7 in which the means for detachably straddling the head portion of the bed provides for selectively positioning the cooler on the said head portion. 50

9. In the art of conditioning air for the occupant of a bed, the steps of simultaneously promoting a downflow of air and cooling the same by directing it in heat exchange relation with a bulk refrigerant at a point slightly above the normal position of the head of such occupant and directing the cooled air in a gentle stream across said position of the head. 55

10. The method described in claim 9 characterized by the use of a refrigerant having ice as a constituent. 60
